DISPENSING PACKAGE

**Theodore F. Onkey, Easton, Conn., assignor to
Roberts Rouge Company, Stratford, Conn., a
corporation of Connecticut**

Application January 29, 1949, Serial No. 73,520

3 Claims. (Cl. 206—56)

1

This invention relates to dispensing packages for material in stick form such as lubricant, dressing compound, polishing compound and the like. Materials of this character are normally prepared in the form of a solid stick and are used by holding the stick in contact with a moving surface, or moving the stick against a stationary surface to abrade off the amount required.

It has been known to encase stick material of this character in containers, the walls of which can be torn away, a portion at a time, to expose the end of the stick as it wears down in use, and it is with this type of container that my invention is concerned.

Since the compound in stick form is often relatively costly, filling of the container from end to end is wasteful because a length of stick which constitutes the shortest practical handle for manipulating the package must be thrown away. It is an object of my invention, therefore, to provide an improved package such that a portion thereof at one end is made to serve as a hollow handle to avoid waste of the stick compound due to this cause.

Furthermore, even when a handle portion is provided at one end of the package, it often happens that the last end of the stick compound is wasted because the package wall has become reduced in length to a point where the short remaining portion of the stick will not be retained in place, and works loose from the handle portion when applied to a relatively moving surface. It is another object of my invention, therefore, to provide an improved anchor for the stick material such that the end portion is firmly retained in place even though the container wall has been largely removed, and so designed that waste of the compound will be reduced to a minimum.

Still a further object of the invention is the construction of a handle equipped dispenser package for stick material using primarily absorbent material such as paper or paste board, but in which the same is inexpensively protected in such a way that the stick material may be introduced in a fluent condition without damage to the package.

Other features and advantages will hereinafter appear.

In the drawing:

Figure 1 is a longitudinal section of the device of the invention, part being shown in elevation.

Fig. 2 is an elevation of the device of my invention showing a portion of the container wall removed in preparation for use.

2

Fig. 3 is a fragmentary section illustrating a modification.

Fig. 4 is a diagrammatic view with parts broken away illustrating the manner in which the device of the invention is used.

Fig. 1 illustrates the invention in the form at present preferred, and shows a cylindrical wall 10 which consists primarily of a tube 11 of paper, cardboard, or other material which can be readily torn or fractured and removed in sections. The wall 10 surrounds a stick 12 of lubricant, dressing compound, polishing compound, or similar solid treating agent to be dispensed. Preferably the tube 11 has a lining 14 of metal foil or other suitable impervious layer which prevents deterioration or discoloration of the stick 12 by constituents of the paper of tube 11, and likewise prevents absorption of any of the ingredients going to make up the stick 12 by the paper of tube 11, which is normally somewhat absorbent.

The cylinder 10 is closed at one end by a sheet metal end wall 16, the periphery of which is crimped to the end of the cylinder 10, in the nature of a false bottom. There is then inserted within and at the bottom of the container thus formed, an insert 17 consisting of a short cylinder 18 preferably of paper, cardboard or the like which has its upper end closed by a sheet metal wall or true bottom 20 peripherally crimped to the end of the short cylinder 18. The wall 20 has an anchor 22 firmly secured to its upper surface. The anchor 22 is preferably a cup-shaped sheet metal stamping having a radial flange 24 as shown in Fig. 1. The insert 17 is designed to have a tight frictional fit in the cylinder 10.

When the container has been completed in the manner described above, the compound with which it is to be filled is reduced to fluent form, preferably by heating the same, is poured into the container and solidifies, as by cooling, to form the stick of compound 12. The metallic lining 14 in the tube 10, and the metal of the wall 20 which presses into contact with this lining, form an ideal mold for the cast of the stick and prevent access of the molten compound to any of the pasteboard or paper parts of the holder where the compound 12 might otherwise be absorbed and adhere to the cylinder 10 upon cooling, or even penetrate the same sufficiently to mar its external appearance, or prevent proper adhesion of a conventional paper cover or label. In forming the stick 12, the material flows around and under portions of the anchor 22, so that the stick will be firmly locked in place when the compound

has set. The anchor 22 may take many forms, but is found to be most serviceable when shaped to provide overhangs which are spaced from the wall 20, forming undercuts into which the liquid compound material may flow. The form of anchor, shown in the drawing is one which is reliable in operation, and at the same time can be simply and inexpensively produced.

Fig. 2 illustrates the first step in using the completed package. Here the cylinder 10 is shown after a portion thereof has been torn off along line 26 exposing the end of the stick 12 for use. Where the material of stick 12 is a polishing compound the same may be applied to the surface of a buffing wheel 40 in the manner shown in Fig. 4. As the stick 12 is worn down by use, the cylinder 10 may be progressively torn away until the stick 12 is substantially used up as shown in Fig. 4. Although little of the stick 12 remains, a firm grip on the package is insured without waste of the compound, since the cylinder portion between walls 16 and 20 is always available as a handle. Furthermore the material of the stick 12 can be used until the upper surface of the anchor 22 is exposed, since it is firmly held in place thereby even though the support afforded by the cylinder 10 has been severely reduced or altogether removed. In this connection it will be noted that the upper surface of anchor 22 is made to extend above the wall 20 to a minimum extent consistent with a firm anchorage in order to confine the waste end of the stick 12 to the shortest possible length.

Fig. 3 illustrates a modified form of the invention in which the insert 17, instead of being frictionally held, is positioned at the bottom of the cylinder 10 and clamped in place by an annular sheet metal ring 16' of channel section which replaces the false bottom 16 of Fig. 1.

Variations and modifications may be made within the scope of this invention and portions of the improvements may be used without others.

I claim:

1. A dispensing package comprising a pasteboard tube having a metallic lining; a stick of compound in said tube and occupying a portion only of its length; an insert comprising a pasteboard tube of smaller diameter and shorter than said first-mentioned tube, and having a sheet metal wall at one end, said insert occupying the remainder of the first-mentioned tube with said end wall in contact with the end of said stick and in peripheral engagement with said metallic lining, and a sheet metal anchor element at-

tached to the inner surface of said end wall, shaped to provide oppositely extending overhangs intimately engaged with and surrounded by the material of said stick.

2. A dispenser container for stick compound which occupies a portion only of the length of the dispenser container comprising a pasteboard tube having a metallic lining; an insert comprising a pasteboard tube of smaller diameter and shorter than said first-mentioned tube, and having a sheet metal wall at one end, said insert occupying an end portion of said first-mentioned tube with said metal end wall facing the stick compound portion of the tube and in peripheral engagement with said metallic lining, and a sheet metal anchor element attached to the inner surface of said end wall and shaped to provide oppositely extending overhangs protruding into the stick compound portion of the tube to intimately engage and be surrounded by the material of the stick compound.

3. A dispenser container for stick compound which occupies a portion only of the length of the dispenser container comprising a tube having a lining impervious to the stick compound; a tubular insert of smaller diameter and shorter than said tube and having a metallic end wall, said tubular insert occupying an end portion of said tube with said metallic end wall facing the stick compound portion of the tube and in peripheral engagement with said impervious lining, and an annular anchor element attached to the inner surface of said end wall and shaped to provide oppositely extending overhangs protruding into the stick compound portion of the tube to intimately engage and be surrounded by the material of the stick compound.
